Primary Examiner — Cynthia Ramirez(74) *Attorney, Agent, or Firm* — Millen, White, Zelano & Branigan, PC; Ryan Pool**CLAIM**

The ornamental design for a bin lid, as shown and described.

DESCRIPTION

FIG. 1 is a perspective view of the bin lid showing my new design.

FIG. 2 is a side view in an open configuration thereof.

FIG. 3 is another side view thereof.

FIG. 4 is top view thereof.

FIG. 5 is a bottom view thereof.

FIG. 6 is a front view thereof.

FIG. 7 is a back view thereof.

FIG. 8 is an exploded perspective view thereof; and,

FIG. 9 is an alternative exploded perspective view thereof. The broken lines in the drawings illustrate portions of the bin lid which form no part of the claimed design.

1 Claim, 9 Drawing Sheets(56)
